UNITED STATES PATENT OFFICE

2,194,474

MINING APPARATUS

Joseph F. Joy, Pittsburgh, Pa., assignor to
Sullivan Machinery Company, a corporation of
Massachusetts

Application June 17, 1936, Serial No. 85,755
Renewed April 5, 1939

7 Claims. (Cl. 262—28)

This invention relates to mining apparatus, and more particularly to improvements in the dust-allaying means for the kerf cutter of an apparatus for cutting coal.

5 An object of this invention is to provide an improved dust-allaying means for the kerf cutter of a coal mining apparatus, whereby the dust created by the cutters of the kerf cutter is effectually allayed. Another object is to provide an 10 improved dust-allaying means for a kerf cutter of a coal mining apparatus, whereby a supply of dust-allaying liquid is conducted through the kerf cutter into the kerf cut thereby, so that the liquid is effectually discharged directly against 15 the walls of the kerf. A further object is to provide an improved dust-allaying means embodying a source of liquid supply, a pumping means, means for conducting the liquid discharged from the pumping means into the kerf cutter, and improved discharge means embodied 20 in the kerf cutter for discharging the liquid from within the kerf cutter into the kerf cut thereby. A still further object is to provide an improved kerf cutter having improved features 25 of construction whereby a dust-allaying liquid may be conducted through the kerf cutter in an improved manner, and embodying improved liquid discharge means for spraying the liquid from within the kerf cutter directly upon the cutters thereof. These and other objects and advantages of the invention will, however, herein-after more fully appear.

In the accompanying drawings, there is shown for purposes of illustration one form which the 35 invention may assume in practice.

In these drawings—

Fig. 1 is a plan view of a coal mining apparatus having embodied therein the illustrative form of the improved dust-allaying means.

40 Fig. 2 is a side elevational view of the mining apparatus shown in Fig. 1.

Fig. 3 is an enlarged view in longitudinal vertical section, taken substantially on line 3—3 of Fig. 1, illustrating the liquid tank structure.

45 Fig. 4 is an enlarged view in longitudinal vertical section, taken substantially on line 4—4 of Fig. 1.

Fig. 5 is an enlarged view in longitudinal vertical section, taken substantially on line 5—5 of Fig. 1.

50 Fig. 6 is an enlarged fragmentary plan view, with the top cover removed, illustrating the improved pumping means.

Fig. 7 is a horizontal sectional view taken substantially on line 7—7 of Fig. 5.

Fig. 8 is a detailed vertical sectional view taken substantially on line 8—8 of Fig. 7.

Fig. 9 is an enlarged plan view of the kerf cutter.

Fig. 10 is an enlarged cross sectional view 5 taken on line 10—10 of Fig. 9.

Fig. 11 is an enlarged cross sectional view taken substantially on line 11—11 of Fig. 9.

In this illustrative embodiment of the invention, the improved dust-allaying means is embodied in a coal mining apparatus of the type known as a universal track cutter, which may be similar in design to that disclosed in my copending application Serial No. 20,826, filed May 10, 1935, although it will be evident that the improved dust-allaying means may be incorporated in mining apparatus of various other types.

As illustrated, the coal mining apparatus generally comprises a wheel-supported base 1 supported on truck wheels 2 adapted to run along a mine trackway 3. Mounted on the forward end of the base for rotation about a vertical axis is a horizontal turntable 4 having pivotally mounted thereon at 5 for swinging movement in a vertical direction with respect thereto, a boom 6. 20 Mounted on the outer extremity of the boom for rotation about the longitudinal axis of the boom, is a rotatable head 7, in turn having pivotally mounted thereon at 8, on an axis at right angles to the head axis, a cutter support 9. Pivotally 25 mounted on the cutter support at 10 for swinging movement with respect thereto about an axis at right angles to the cutter support axis, is a swingable hanger 11 carrying an elongated plane kerf cutter 12. As described in the above 30 mentioned application, devices are provided for rotating the turntable, for swinging the boom relative to the turntable, for rotating the head relative to the boom, and for swinging the cutter support relative to the head; but since these devices do not per se enter into this invention, further detailed description thereof is considered 35 unnecessary.

Now referring to the improved dust-allaying means, it will be noted that mounted on and 40 shaped to fit the top of the base 1 is a low compact, horizontal tank 14 for containing a liquid, preferably water, the tank provided with usual filling caps 15 and being of a fabricated construction preferably composed of sheet metal 45 and comprising an outer shell 16 having transverse partitions 17 extending vertically between the top and bottom of the shell, at points spaced longitudinally of the tank, and these partitions 50 cooperate with a plurality of brace rods 18 in 55

the bracing of the tank shell. Each of the transverse partitions is provided at the top and bottom thereof with apertures 19 and 20 for connecting together the chambers within the tank 5 formed by the partitions, so that the interior of the tank is in reality in the form of one elongated chamber. Arranged within a chamber 21 at the forward end of the tank and having a hinged cover 22, is a pump 23 of any appropriate 10 commercial design, driven by a motor 24, herein preferably an electric motor, having its power shaft 25 connected through a coupling 26 to the shaft 27 of the pump. The pump intake 28 is connected through a conduit 29 with the forward 15 end of the tank chamber, and through a conduit 30 with the rearward end of the tank chamber, and a valve 31 is provided for connecting the pump intake selectively to these conduits 29 and 30, so that the pump may receive its liquid supply 20 from either end of the tank. Such an arrangement is desirable, particularly when the machine is operating on an incline so that only one conduit, due to the inclination of the tank, is below the liquid level. Each of the conduits 29 and 30 25 is provided with an automatic check valve 32 and 33, so that the liquid in the conduits cannot flow in a reverse direction back into the tank.

The pump discharge 34 is connected by a flexible conduit 35 extending downwardly, as shown 30 in Fig. 4, through an opening 36 in the top of the base frame and passing through the base, over the front truck wheel axle, beneath the turntable, and upwardly through the open center of the turntable; the conduit extending longitudinally through the boom 6, and at its forward end passing out through an opening 37 (see Fig. 5) in the bottom of the boom. The forward end of this conduit is connected through an automatic check valve 38 to a short pipe section 39 threaded at 40 within the rearward portion of 40 the hanger frame 11, on which the kerf cutter is mounted. The pipe section 39 communicates through a passage 41 in the hanger frame with a right-angle passage 42 formed axially within a 45 screw 43 threaded within the hanger frame. The hanger frame is provided with a recess 44 within which is seated a block member 45 tightly clamped in position against the bottom of the recess by the head of the screw 43, and the member 45 is formed with a chamber 46 surrounding the screw and with which the passage 42 communicates.

As shown in Figs. 7 and 8, the chamber 46 is connected by a conduit in the form of a bent 55 tube 47, threadedly connected at one end within the block member 45 and at its opposite end within a block member 48, similar to the block member 45 and similarly clamped in position by a screw 49. The member 48 likewise has an annular chamber 50 surrounding the screw and communicating with an axial passage 51 formed in the screw 49; and this passage 51 communicates through a passage 52 with a right-angle passage 53 formed in a depending portion 54 of 60 the hanger frame 11. Threaded within the forward side of the depending portion 54 is a short pipe section 55 communicating with the passage 53 and extending forwardly through a stuffing box 56 mounted within the rear end of the kerf 65 cutter, the forward portion of the pipe 55 being telescopically arranged within a longitudinal bore 57 formed in the kerf cutter. As is usual in mining apparatus of the type disclosed, the kerf cutter is mounted within a longitudinal guideway 70 75 formed in the hanger frame 11, and threaded

at 59 within the rearward portion of the kerf cutter is an adjusting screw 60 having its head 61 abutting the forward face of the depending portion 54 of the hanger frame. By adjustment of the screw 60 the kerf cutter may be moved 5 longitudinally within its guideway 58 on the hanger frame to take up any slack in the endless cutter chain 62 mounted for circulation about the margin of the cutter bar 63 of the kerf cutter. The telescopic arrangement of the pipe 55 within the bore 57 permits such longitudinal adjustment 10 of the cutter bar with respect to the hanger frame while maintaining, due to the stuffing box 56, a fluid-tight seal between the parts.

Communicating with the forward end of the 15 bore 57 in the cutter bar is a longitudinal passage 65, in turn communicating with a longitudinal passage 66 formed within a T-shaped member 67 rigidly welded in position in a slot 68 in the cutter bar, as shown in Figs. 9 and 10. 20 This T-shaped member is formed with a transverse passage 69 communicating with the passage 66 and with passages 70 and 71 respectively formed in the longitudinal spacing plates 72, 72 of the cutter bar. The transverse passages 70 and 25 71 respectively communicate with vertical passages 73 and 74 respectively, formed in the bar members 72 and communicating with aligned passages 75 and 76 formed respectively in the top and bottom plates 77, 77 of the cutter bar, the 30 plates 77 rigidly secured to the spacing plates 72 in a well known manner.

The passages 75 and 76 communicate with transverse passages 78 formed in the plates 77, 35 and extend out through enlarged openings 79 formed in the side edges of the plates 77. The openings 79 are threaded at 80 to receive suitable plugs so that certain of the passages 78 may be blocked off if desired, thereby to vary the quantity of liquid discharged from the cutter 40 bar.

The cutter chain 62 is guided in a guideway 81 formed about the margin of the cutter bar, and the passages 78 are so located with respect to the cutter chain guide that the liquid discharged 45 therefrom, as hereinafter described, is sprayed directly against the cutters 82 of the chain. There are series of vertical passages 73, 74 formed in the plates 72 at the opposite sides of the bar, at longitudinally spaced points, and these series 50 of passages are connected together by longitudinal channels 83 formed in the plates 72; and a series of the discharge passages 78 is provided communicating with the vertical passages 73 and 74, so that the liquid is discharged laterally from the 55 cutter bar substantially along the entire length of the cutting portion thereof.

The mode of operation of the improved dust- 60 allaying means will be clearly apparent from the description given. The mining apparatus is propelled along the mine trackway in the manner described in the copending application above referred to, and when the apparatus is located adjacent the coal face, the boom, head and cutter support of the cutter adjusting mechanism are 65 adjusted to locate the kerf cutter in the desired position with respect to the coal face. The cutter bar is then sumped in, moved arcuately across the face, and thereafter withdrawn from the coal to form a kerf in the coal. During the kerf cutting operation, the pump 23 driven by the motor 24 may operate to pump liquid from the tank 14 through one or the other of the conduits 29, 30 and through the discharge conduit 35 extending 70 along the boom, past the check valve 38, and 75

through pipe 39 to the passage 41 in the cutter bar hanger. The liquid flows from the passage 41 through passage 42, chamber 46, the tube 47, the chamber 50, passages 51, 52 and 53, the telescoping connection 55, 57 between the hanger frame and the cutter bar, and through passages 65, 66, 69, 70, 71, 73, 74, 75, 76 and 78; the liquid being discharged transversely of the bar directly against the walls of the kerf and on the cutters 5 of the cutter chain so that the dust created by the cutters during the cutting operation is effectually allayed. The flexible conduit between the pump and the kerf cutter permits the latter to be adjusted into any desired position with respect 10 to the portable base, while the flow of liquid from the tank to the kerf cutter discharge passages is always maintained. If the apparatus is operating on an incline so that only one of the supply conduits 29, 30 is below the level of the liquid 15 in the tank, the valve 31 may be operated to close the supply conduit which is above the liquid level, in an obvious manner. The check valve 38 in the discharge conduit 35 and the check valves 32 and 33 in the supply conduits 29 and 30 permit 20 free flow of liquid through the conduits into the kerf cutter, while they automatically prevent reverse flow of the liquid through the conduits. 25

As a result of this invention it will be noted that an improved dust allaying means is provided for the kerf cutter of a coal mining apparatus, so that the dust created by the kerf cutter during the cutting operation is effectually allayed. It will further be noted that by forming 30 the liquid conducting passages directly within the kerf cutter, it is made possible to discharge liquid directly against the wall of the kerf and on the cutters of the kerf cutter. It will still further be evident that by mounting the liquid supply tank directly over the body of the mining 35 apparatus, it is possible to carry directly on the apparatus a relatively large quantity of dust-allaying liquid, and by the provision of the motor-driven pump it is possible to obtain a relatively powerful spraying action of the liquid as it 40 is discharged from the passages in the kerf cutter directly within the kerf, the liquid discharging from the kerf cutter passages with a jet-like spraying action. Other uses and advantages of the improved dust-allaying means will be clearly 45 apparent to those skilled in the art.

While in this application there is shown, for purposes of illustration, one form which the invention may assume in practice, it will be understood that this form is shown for illustrative purposes only, and that the invention may be modified and embodied in various other forms without departing from its spirit or the scope of the appended claims.

What I claim as new and desire to secure by 60 Letters Patent is:

1. In a mining apparatus, the combination with a portable base and a kerf cutter swivelly mounted on said base to swing relative thereto about an axis perpendicular to the plane of the kerf cut thereby, of dust allaying means for the kerf cutter including a liquid supply tank mounted on said base, a pump, means for conducting the liquid discharged from said pump to the kerf cutter irrespective of the position of the latter about its swivel including passage means extending through the kerf cutter swivel, and means for discharging said liquid from within the kerf cutter into the kerf cut thereby.

2. In a dust allaying means for coal mining machines, the combination with a support and

a kerf cutter pivotally mounted thereon to swing relative thereto about an axis perpendicular to the plane of the kerf cut thereby, of means for supplying a dust allaying liquid through the kerf cutter into the kerf cut thereby irrespective of the position of said kerf cutter about its pivot relative to said support including liquid conducting passage means extending through the pivotal mounting of the kerf cutter.

3. In a dust allaying means for kerf cutters, the combination with a support, a hanger frame swivelly mounted thereon, and a kerf cutter carried by said swivelled hanger frame, said kerf cutter swingable with said hanger frame about an axis perpendicular to the plane of the kerf cut thereby, of means for supplying dust allaying liquid through the kerf cutter into the kerf cut thereby including liquid conducting passage means extending through the swivel mounting of said swivel frame, said passage means including a fluid conducting passage in said hanger frame and a fluid conducting passage in said support and with which said hanger frame passage communicates in all swivelled positions of the hanger frame relative to said support.

4. In a mining apparatus, the combination with a support and a kerf cutter swivelly mounted on said support to swing relative thereto about an axis perpendicular to the plane of the kerf cut thereby, of dust allaying means for the kerf cutter including a source of liquid supply, and means for conducting liquid from said source to the kerf cutter irrespective of the position of the latter about its pivot relative to said support including passage means extending through the swivel mounting for the kerf cutter.

5. In a mining apparatus, the combination with a support and a kerf cutter swivelly mounted on said support to swing relative thereto about an axis perpendicular to the plane of the kerf cut thereby, of dust allaying means for the kerf cutter including a source of liquid supply, means for conducting liquid from said source to the kerf cutter irrespective of the position of the latter about its pivot relative to said support including passage means extending through the swivel mounting for the kerf cutter, and means for conducting liquid from said passage means internally within the kerf cutter and for discharging the liquid from within the kerf cutter into the kerf cut thereby.

6. In a mining apparatus, the combination with a support, a hanger frame swivelled on said support and a kerf cutter mounted on said hanger frame to swing with the latter relative to said support about an axis perpendicular to the plane of the kerf cut by said kerf cutter, of dust allaying means for conducting a dust allaying liquid to said kerf cutter irrespective of the swivelled position of the latter relative to said support including a source of liquid supply and means for conducting liquid from said source to the kerf cutter including a liquid connection with said liquid source at the side of said hanger frame opposite to that from which said kerf cutter projects, passage means for conducting liquid from said liquid connection through said hanger frame to said kerf cutter, and communicating passage means extending through said kerf cutter for conducting liquid through the kerf cutter and for discharging the liquid into the kerf cut thereby.

7. In a mining apparatus, the combination with a support, a hanger frame swivelled on said support, a kerf cutter mounted on said hanger

- frame for longitudinal adjustment relative thereto and swingable with said hanger frame relative to said support about an axis perpendicular to the plane of the kerf cut by said kerf cutter and means for adjusting said kerf cutter longitudinally relative to said hanger frame, of dust allaying means for said kerf cutter for conducting a dust allaying liquid to the kerf cutter irrespective of the longitudinally adjusted position of the latter relative to said hanger frame or the swivelled position of said hanger frame relative to said support including a source of liquid sup-

ply, a liquid connection with said liquid source at the side of said hanger frame opposite to that from which said kerf cutter projects, passage means for conducting liquid from said liquid connection through said hanger frame to said kerf cutter including a telescopic fluid connection between said hanger frame and the inner end of said kerf cutter, and communicating passage means extending through said kerf cutter for conducting the liquid through said kerf cutter into the kerf cut thereby.

JOSEPH F. JOY.
